CLAIM

The ornamental design for a nursing bag, as shown and described.

DESCRIPTION

FIG. 1 is a perspective view of a nursing bag in accordance with my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is perspective view of another embodiment of the nursing bag shown in FIG. 1;

FIG. 9 is front view of another embodiment of the nursing bag shown in FIG. 1;

FIG. 10 is rear view of another embodiment of the nursing bag shown in FIG. 1;

FIG. 11 is right side of another embodiment of the nursing bag shown in FIG. 1;

FIG. 12 is left side of another embodiment of the nursing bag shown in FIG. 1;

FIG. 13 is top view of another embodiment of the nursing bag shown in FIG. 1; and,

FIG. 14 is bottom view of another embodiment of the nursing bag shown in FIG. 1.

The broken lines shown in all of the figures form no part of the claimed design.
